UNITED STATES PATENT OFFICE

GEORG FAULSTICH, OF CASSEL, GERMANY

RUSSIAN BOOT

Application filed March 9, 1928, Serial No. 260,407, and in Germany March 17, 1927.

This invention relates to an improved Russian boot, of which the leg is provided with a plaited longitudinal part consisting of folds therein, while a contracting elastic 5 insertion is sewn to the inner parts of the single folds and covered by the latter toward the outside.

The improved Russian boot is illustrated on the accompanying drawing, in which 10 Fig. 1 is a side view of the same, while

Figs. 2 and 3 show the same with cut-open upper in a front view of the plaited longitudinal part and in a rear view of the elastic insertion thereof, and

15 Fig. 4 is a cross-section through the plaited longitudinal part of the leg with the elastic insertion sewn to the inner parts of the single folds.

The leg *a* of the Russian boot is provided 20 with a plaited longitudinal part *b* extending from the top end of the leg down to the lower end thereof adjoining the tongue *c* of the upper. The single folds of the plaited longitudinal part *b* of the leg are at their rear

25 parts joined by a contracting elastic insertion *d* sewn thereto at *e* and fixed at its lateral ends between the leg *a* and the lining *f* thereof, a wedgelike leather strip *g* being preferably interposed between the lateral ends of the insertion and the leg (see Fig. 4) for strengthening purposes.

30 Preferably, between the leg *a* and the lining *f* stiffening insertions *h* may be provided, which can be inserted or removed through 35 flaps *i* at the top ends of the leg *a*, which flaps can be buttoned at *k* to the inner surface of the leg.

What I claim, is:

40 1. In a Russian boot the formation of the front portion of the leather of the leg portion to form a number of deep undulating folds lying close together tapering in downward direction and extending from top to bottom of the leg and a backing of elastic 45 webbing on the folded portion of the leather sewn on the undulations at the lower end of said folds.

45 2. In a Russian boot the formation of the front portion of the leather of the leg portion to form a number of deep undulating

50 folds lying close together tapering in downward direction and extending from top to bottom of the leg portion, a backing of elastic webbing on the folded portion of the leather sewn on the undulations at the lower end of 55 said folds, and pockets adapted to be closed arranged on the rear side of the leg portion at the right and left of said folded portion, said pockets designed to receive stiffening insertions.

55 In testimony whereof I have hereunto set my hand.

GEORG FAULSTICH.
